UNITED STATES PATENT OFFICE.

EDWARD E. SMITH, OF NEW YORK, N. Y.

ASH-SIFTER FOR STOVES.

SPECIFICATION forming part of Letters Patent No. 396,178, dated January 15, 1889.

Application filed May 17, 1888. Serial No. 274,120. (No model.)

To all whom it may concern:

Be it known that I, EDWARD E. SMITH, of the city, county, and State of New York, have invented a new and Improved Ash-Sifter for 5 Stoves, of which the following is a full, clear, and exact description.

My invention relates to ash-sifters, and particularly to such apparatus as applied to stoves or heaters; and the invention has for 10 its object to provide a simple, inexpensive, and easily-operative sifter of this character.

The invention consists in certain novel features of construction of the sifter and of the stove or heater in which it is fitted, and also 15 in certain combinations of parts of the apparatus for carrying out various principles of action of the sifting devices, all as hereinafter described and claimed.

Reference is to be had to the accompanying 20 drawings, forming a part of this specification, in which similar letters of reference indicate corresponding parts in all the figures.

Figure 1 is a vertical sectional elevation of the lower portion of a stove fitted with my 25 improved ash-sifting devices. Fig. 2 is a plan view, in smaller scale, of a modified form of guard plate or ring to be placed over the ash-sifter in a stove of rectangular form. Fig. 3 is a plan view in horizontal section on the line 30 3 1 in Fig. 1, and with the sifter-sections partly broken away. Fig. 4 is a detail inside face view with the guard-plate and shaker-bar in section on the line 2 2 in Fig. 1, and Fig. 5 is a dismembered perspective view of the three 35 sections of the ash-sifter raised one from or above the other.

The stove-body A (partly shown in Fig. 1 of the drawings) is of ordinary round cross-sectional form; but its portion a, below its grate 40 B and base-flange a', is made a little deeper than usual to accommodate the sifter devices and give room at the base of the stove for the ashes and cinders which are discharged from the sifter into two separate compartments, C 45 D, formed at opposite sides of a transverse partition, E, which is cast upon or fixed to and across the bottom plate, e, of the stove, and is about three inches (more or less) in height.

The vertical spindle F, which supports the 50 three sections G H I of the sifter device, is journaled at its upper end in the arm or

bracket b, which supports the stove-grate B, and at its lower end the spindle is journaled to the top of the partition E, and preferably by a pin on the partition entering a hole in 55 the shaft. The sifter-sections G H I will be hereinafter more particularly described; but I here state that all three of them are held together and on the spindle, so as to be oscillated horizontally as one structure by means 60 of a shaker-bar, J, which is fixed to the upper section, G, and projects through a horizontal slot, j, made in the lower body or wall, a, of the stove.

It is desirable to close this slot j during the 65 operation of the sifter to prevent escape of dust into the room, and to accomplish this I have hung upon the shaker-bar J a dust-guard plate, K, which moves with the bar and always 70 covers the slot j. The plate K normally rests at 75 its lower edge upon a couple of lugs or lips, k k, on the inner face of the stove-wall a, and at its upper edge fits loosely behind a couple of lugs, l' l', which are cast on or fixed to the under side of an ash-guard plate, L, which is 80 bolted between the base-plate a' of the upper or fire-pot section of the stove and the flanged top of the lower stove-section, a, and is provided with a central opening conforming to the lower opening of the base-plate a', and 85 has a depending flange, l, all around said central opening. This flange l of the plate L guides all the ashes shaken through or dumped from the stove-grate B safely into the top section, G, of the sifter.

In operating the sifter it is desirable that its shaker-bar J be prevented from striking the ends of the stove-slot j, in which it works, to avoid noise, and to accomplish this, and at the same time assist in oscillating the sifter, 90 I have provided a plate-spring, M, which is held to the stove-body by three lugs, m' m² m³, as presently explained, and at its upper end is notched at m, to fit loosely upon and around the lower edge of a flange, O, which is fixed 95 to or forms a part of the dust-guard plate K, and is provided at or near its opposite ends with two shoulders, o o, which strike the spring M before the shaker-bar reaches the ends of the slot j and flex the spring or put it in tension, and as the spring is stiff enough to stop 100 the shaker-bar before it reaches either end of

the slot j , it is manifest that the rebound of the spring will materially assist in oscillating the sifter in the stove.

The spring-supporting lugs m' m^2 m^3 are preferably cast upon the inner face of the stove-body section a , and the lowest lug, m' , has a rabbet, into which the lower end of the spring rests. The center lug, m^2 , has a lip, m^4 , which overlies the outer edge of the spring, and this lug m^2 forms a fulcrum, on which the spring bends as the shaker-bar J is moved toward the right hand, while the upper lug, m^3 , against the side of which the opposite face of the spring rests, forms a fulcrum, on which the spring receives a shorter bend as the bar J is moved toward the left hand by the operator. This arrangement of the spring in its supporting-lugs has for its purpose to cause the spring to offer a greater resistance by practically shortening it as the shaker-bar is moved from right to left, and to offer less resistance by practically lengthening it as the bar is moved in the other direction, and thus compensate for the increased power which is naturally applied by a right-handed operator in moving the shaker-bar toward the left, than is exerted in the return movement of the bar and sifter.

It is manifest that I am not limited to the use of a spring which offers resistance to the oscillatory movements of the shaker-bar of an ash-sifting device, and which offers a greater resistance on one stroke of the bar than on its other stroke, in combination with a dust-guard plate, K , which in this case is a connection on the shaker-bar on which the spring operates, as the spring may be used with any connection to the bar, or so as to act directly thereon in substantially the manner above described. Furthermore, any ordinary oscillatory stove-grate having a shaker-bar is an ash-sifting device within the scope of this part of my invention.

Fig. 2 of the drawings illustrates an ash-guard, L' , having the same purpose as the guard L above described, but adapted to fit at the bottom of the fire-pot of a rectangular stove and provided with a face which inclines funnel-like to the round central opening through which the ashes and cinders will fall into the top section, G , of the sifter. It is obvious that the face or floor i^2 of the ash-guard may have any outer marginal shape necessary to fit it to round, oval, square, or other shaped stoves or heaters and allow them to discharge the ashes safely into the sifter.

I will now particularly describe the sifter proper, as follows: The sifter-sections G H I are made preferably of cast-iron; but they may be made of sheet metal, if desired. The upper edges of the sections H I are preferably provided with lips or flanges P , forming rabbed seats for the sections G H , respectively, and the sections G I have marginal lugs r , through which stove-bolts R are passed to bind all three sections together after they shall have been placed on the common shaft

F of the sifter. To make sure that the sections shall not slip around horizontally on each other, I provide them at their joints with lugs or lips S on one section, which engage sockets or recesses s in the adjacent section. 70

The shaft F is provided with a series of prongs, T , preferably three in number, and which are adapted to enter sockets t , provided for them at the under side of the lower sifter-sections, H I , as said sections are slipped onto the shaft, and after the upper section is put on the shaft a retaining-pin, f , is passed through the shaft above its hub. (See Fig. 1 80 of the drawings.)

The imperforate floor or bottom g of the sifter-section G inclines downward from its upper radial edge, g' , to its lower radial edge, g^2 , whence the mixed ashes and cinders fall 85 onto the higher edge, h' , of the downwardly-inclined floor h of the sifter or separator section H , the lower radial edge, h^2 , of which discharges the cinders into the cinder-compartment D after they have been freed from the 90 ashes and dust which have fallen through the numerous perforations h^3 of the inclined bottom h of the sifting-section H .

The ash-conduit section I of the sifter has an imperforate inclined floor, i , which is upturned at i' to meet the edge h' of the sifting-section H to receive ashes falling through the upper part of the floor h of section H , and extends around under this perforated floor to a discharge edge, i^2 , which extends radially sufficiently far around over and past the stove-body partition E to assure passage of the ashes only into the ash-compartment C of the stove. When the sifter-sections G H I are held together in operative position, the radial edges 105 $g' g^2 h' i'$ thereof range about or nearly in a vertical plane. The cinder-discharge edge h^2 of the section H ranges back from this line or from the vertical plane of the edge i' of the section I for about twenty-five degrees of a 110 circle to give space between said edge h^2 and the upper or receiving end of the section I for the free discharge of cinders from over said edge h^2 during the operation of the sifter, and the ash-discharge edge i^2 of the section I is 115 extended around, preferably, to the position indicated by the dotted line in Fig. 3 of the drawings, thus making the inclined floor i of the section I extend for but little more than one-half way around the apparatus, while 120 assuring free discharge of the ashes over the edge i^2 into the compartment C and without contact with the step or shoulder h^4 of the sifting-section floor, which shoulder faces the open mouth or discharge end of the section I . 125

When the sections G H I , having inclined floors communicating as above described, are put together, the top of the section G and the outlet i^2 of the section I , with the edge h^2 of the sifting-section H , stand about in parallel 130 horizontal planes, and the gradual downward incline of the floor h of the section H is made by giving this section a helical or twisted bodily form, and the section I also has a heli-

cal or twisted form to allow it to fit onto the section H above it. The floors *g h i* of the three sections G H I, in addition to their general downward incline, have a downward pitch radially of the sections from their hubs or centers to their rims, thus causing the ashes and cinders to approach the outside or rims of the sections, where they are agitated more thoroughly than would be possible were the floors level radially or inclined downward radially toward the hubs of the sections.

As shown in Fig. 5 of the drawings, the floor *h* of the sifting-section H is provided with a series of vertical shoulders or steps, *h⁴*, preferably three, and extending radially from the hub of the section, where the shoulders are highest, to the rim or side wall of the section, where the shoulders merge into or are about level with the general surface of the floor *h*, this wedge shape of the shoulders or steps being partly due to the radial downward incline of the floor. The object of this stepped construction of floor *h* is to give an abrupt fall to the ashes and cinders passing down the floor, so as to turn them over and over and more thoroughly agitate them to clear the cinders from the ashes than a gradually-inclined floor alone would effect. It will be noticed that the floor-perforations *h³* commence at points forward of the upper edge, *h'*, and the upper shoulder, *h⁴*, thus leaving plain surfaces *h⁵*, about an inch in width, next the edge *h'*, and shoulders *h⁴*, onto which the cinders may fall and then slide freely downward, as they would not do if these parts *h⁵* had perforations into which the cinders would be liable to stick as they fell from the upper section, G, and over the upper steps or shoulders, *h⁴*. These plain parts *h⁵* thus avoid clogging of the sifting-section.

It will appear that a part, H', of the floor *h* of the section H, next the discharge edge *h²* of this floor and extending back of the edge for about twenty-five degrees of a circle, or to the last step or shoulder, *h⁴*, of the floor, is preferably not provided with perforations, which are unnecessary, as the ashes will have already fallen through the perforations in the higher parts of the floor; but this imperforated portion H' of the floor prevents escape of ashes into the cinder-compartment D during the oscillation of the sifter, at which time said portion H' will always overlie the partition E at the base of the stove, as the arc of movement of the sifter will extend only for a distance equaling the length of this part H', or between the edge *h²* and last step or shoulder *h⁴* of the floor of the middle section, H. A pendent lip, *h⁶*, may be provided at the edge *h²*, if preferred, and as indicated in dotted lines in Fig. 5 of the drawings.

The hub portion of the sifter-sections G H I curve upward from the floors of said sections, and the tops of the two lower sections, H I, preferably describe a spiral line around the shaft F, which allows these sections H I to be easily cast to nicely fit around the shaft

without requiring a boring or reaming of their bearing on the shaft, and thus facilitates their cheap manufacture.

From the aforesaid description it will appear that the inclined floor *g* of the upper ash-receiving section, G, extends clear around it, thereby causing all the ashes falling from the fire-pot of the stove into it to be discharged upon the upper end of the inclined perforated floor *h* of the sifting-section H, down which the cinders travel for the full length of said floor as the sifter is oscillated by its shaker-bar J; and meanwhile the ashes fall from the cinders through the perforations *h³* of the floor of section H—some of the ashes directly into the ash-compartment C, but most of them fall into the ash-conduit section I—and are discharged from its edge *l²* into the compartment C, while all the cinders passing down the perforated floor of the section H are discharged from its imperforated part H' and over its edge *h²* into the cinder-compartment D of the stove.

It is manifest that a sifter constructed and operating as above described assures a thorough sifting of all the ashes falling from the stove by mechanism which is very compact and occupies a comparatively small space at the base of the stove.

Doors of any preferred kind may be fitted in the stove-body section a to give access to the ash and cinder compartments C D of the stove, or to these compartments and the entire sifting apparatus arranged above them, and separate ash and cinder receiving pans may be placed at the base of the stove below the sifter, as will be readily understood.

Having thus described my invention, what I claim as new, and desire to secure by Letters Patent, is—

1. The combination, with a stove or heater, of an ash-sifter fitted therein below the fire-pot for horizontal oscillation, consisting of an upper ash-receiving section having an imperforate sloping floor and a lower sifting-section having a sloping perforated floor, and said sections relatively arranged to cause the upper section to discharge the mixed ashes and cinders onto the higher portion of the perforated floor of the lower section, substantially as herein set forth.

2. The combination, with a stove or heater, of an ash-sifter fitted below the fire-pot for horizontal oscillation, consisting of a sifting-section having a sloping perforated floor receiving the mixed ashes and cinders from the fire-pot, and with a lower ash-receiving section having an imperforate floor receiving the ashes from the sifting-section and discharging them at a place separate from the cinders falling from the sifting-section, substantially as herein set forth.

3. The combination, with a stove or heater, of an ash-sifter fitted below the fire-pot for horizontal oscillation, consisting of an upper ash and cinder receiving section having an imperforate sloping floor, an intermediate

next lower sifting-section having a sloping perforated floor, receiving at its upper part the mixed ashes and cinders from the upper section, and a lower section having an imperforate floor receiving the ashes from the sifting-section and discharging them at a place separate from the cinders discharged from the sifting-section, substantially as herein set forth.

10 4. An oscillatory ash-sifter consisting of a supporting-shaft and three sifter-sections thereon, or an upper ash and cinder receiving section having an imperforate sloping floor, an intermediate next lower sifting-section having a sloping perforated floor receiving at its upper part the mixed ashes and cinders from the upper section, and a lower section having an imperforate floor receiving the ashes from the sifting-section and discharging them at a place separate from the cinders discharged from the sifting-section, and bolts R, holding the sifter-sections together vertically, substantially as herein set forth.

5 5. An oscillatory ash-sifter consisting of a supporting-shaft and three sifter-sections thereon, or an upper ash and cinder receiving section having an imperforate sloping floor, an intermediate next lower sifting-section having a sloping perforated floor receiving at its upper part the mixed ashes and cinders from the upper section, and a lower section having an imperforate floor receiving the ashes from the sifting-section and discharging them at a place separate from the cinders discharged from the sifting-section, bolts R, holding the sections together vertically, and interlocking lugs and sockets at the section-joints preventing independent axial movement of the sections during their oscillation, substantially as herein set forth.

10 6. In a horizontally-oscillating ash-sifter having upper, middle, and lower sections, substantially as described, the section H, having a perforated sloping floor, h, provided with one or more steps or shoulders, h⁴, substantially as herein set forth.

15 7. In a horizontally-operating ash-sifter having upper, middle, and lower sections, substantially as specified, the sifter-section H, having a sloping floor perforated at h³ and provided with shoulders h⁴, and having plain portions h⁵ next its upper edge, h', and the shoulders h⁴, substantially as herein set forth.

10 8. The combination, in an ash-sifting apparatus for stoves, of a partition, E, at the base of the stove, forming compartments C D therein, a vertical spindle, F, having supports or shoulders, as T, sifter-sections I H G, supported on said shoulders and on each other,

and said section G formed with an imperforate floor, g, and said section H formed with a floor, h, mainly perforated and having an imperforate portion, H', next its edge discharging the cinders into the compartment D, and said section I having an imperforate floor, i, receiving ashes from the section H and discharging them into the compartment C, and all three sections held together for simultaneous horizontal oscillation, substantially as herein set forth.

70 9. The combination, with a casing or frame having a slot and an oscillatory sifting device supported in said casing and provided with a shaker-bar entering the casing-slot, of a spring held to the casing, and against which the shaker-bar or a connection therewith may strike, substantially as described, whereby the resistance of the spring will prevent noisy contact of the shaker-bar at the ends of the slot in which it works, substantially as herein set forth.

10 10. The combination, with a casing or frame having a slot, and an oscillatory sifting device supported in said casing and provided with a shaker-bar entering the casing-slot, of a spring held to the casing and stop-lugs on the casing for the clamped end or part of the spring, substantially as described, whereby the spring will be held in a manner to have greater resistance against the movement of the bar in one direction than in the other direction, as and for the purposes set forth.

15 11. The combination, with the shaker-bar of an ash-sifting device passed through a slot in the sifter-support, of a dust-guard plate, K, on the bar at the slot and provided with shoulders o o, and a spring held to the sifter-support and in the path of said shoulders to be struck thereby, to prevent contact of the shaker-bar with the ends of the slot through which it works, substantially as herein set forth.

10 12. The combination, with the shaker-bar of an ash-sifting device passed through a slot in the sifter-support, of a dust-guard plate, K, on the bar at said slot and provided with shoulders o o, and a spring, M, held in lugs m' m² m³ on the sifter-support and in the path of said shoulders, substantially as shown and described, whereby the resisting-power of the spring will be increased and diminished at opposite strokes of the shaker-bar, substantially as herein set forth.

EDWARD E. SMITH.
